NOZZLE FOR A VACUUM CLEANER

Montgomery Ferar, Huntington Woods, Mich., assignor
to Whirlpool Corporation, a corporation of Delaware

Filed Apr. 10, 1961, Ser. No. 64,711

Term of patent 14 years

(Cl. D9—2)

FIG. 1.

FIG. 2.

FIGURE 1 is a top perspective view of a nozzle for a vacuum cleaner, showing my new design;

FIGURE 2 is a side elevational view thereof;

FIGURE 3 is a top plan view thereof; and

FIGURE 4 is a front elevational view thereof.

The back, not shown, is substantially plain, as indicated by FIGURES 2 and 3.

I claim:

The ornamental design for a nozzle for a vacuum cleaner, as shown and described.
